Patented Dec. 6, 1921.

UNITED STATES PATENT OFFICE.

ALPHONS ZIPFEL, OF LACHEN, SWITZERLAND.

WEAVING-HEALD AND PROCESS FOR MANUFACTURING THE SAME.

1,399,237.

Specification of Letters Patent.

Patented Dec. 6, 1921.

Application filed March 31, 1921. Serial No. 457,479.

(GRANTED UNDER THE PROVISIONS OF THE ACT OF MARCH 3, 1921, 41 STAT. L., 1313.)

To all whom it may concern:

Be it known that I, ALPHONS ZIPFEL, a citizen of the Republic of Switzerland, residing at Lachen, Switzerland, have invented certain new and useful Improvements in Weaving-Healds and Processes for Manufacturing the Same, (for which applications have been filed in Switzerland, September 26, 1914, Patent No. 69,158; Ger-

10 55 10 55
many, October 5, 1914, Patent No. 289,895; Austria, September 20, 1915, Patent No. 73,428; Hungary, September 23, 1915, Patent No. 69,710; France, September 25, 1915, Patent No. 479,835; England, September 25,

15 60 15 60
1915, Patent No. 136,48/15, and Pologne, November 13, 1919, appln. No. 7,587/19;) and I do hereby declare the following to be a clear, full, and exact description of the invention, such as will enable others skilled

20 65 20 65
20 in the art to which it appertains to make and use the same, reference being had to the accompanying drawings, and to letters or figures of reference marked thereon, which form a part of this specification.

25 70 25 70
25 The present invention relates to improvements in healds for weaving looms and the like, and the process for manufacturing the same.

30 75 30 75
30 Weaving healds for looms made of double steel wire are already known which have lengthened ears at their ends for receiving the heald bars and have a thread eye arranged between these ears. The ears on the ends of the healds have been formed by bending out the double steel wire and winding the ends about the shaft and securing them to the latter by soldering.

35 80 35 80
35 These healds have the disadvantage that the ears are thicker than the double strand 40 85
40 of wire and therefore take up too much space as regards the juxtaposition of the healds on the heald rods, and consequently also increase the total weight of the healds. Also, it can occur in such constructions that 45 90
45 the healds owing to some thickened portion may catch and remain suspended when the shafts are lifted or lowered and consequently interfere with one another's correct predetermined movement.

50 95 50 95
50 It has been suggested in the case of healds

acting as feeler rods in warp stop motions, to use instead of the wire ears thin steel plates having ears formed upon them and which lie at right-angles to the heald rods. It has however not been found possible to obtain a suitable method of connecting the small plates with the double steel wire which will satisfy all desired conditions.

55 60 55 60
The present invention relates to a means whereby a loom heald may be made of double steel wire and have ears at both ends of the heald shaft for connection to the heald rods, such ears being in the form of steel plates. The invention further relates to a process for manufacturing such articles.

65 70 65 70
According to the present invention the heald shafts are arranged to lie with the bent out ends of the wire parts engaging in the correspondingly shaped slots in small plates and these parts of the wire are connected with the small plates by soldering so that the heald at the connection point between the heald shaft and steel plate will at the most not be thicker than an ordinary wire of the wire shaft.

75 80 75 80
75 These healds are formed by splitting the double wire and bending outward the two ends of the wire shaft, placing these in the correspondingly shaped stamped out slots of the small plates of steel or the like. The bent ends of the wire shaft are then pressed into the notches in the steel plates and subsequently connected to the plates by soldering.

85 85
85 The invention is more particularly described with reference to the accompanying drawings, in which:—

90 90
90 Figures 1 and 2 show one form of construction by way of example in side and front view respectively, while

95 95
95 Figs. 3 to 10 show different steps in the process of manufacturing the articles,

95 95
95 Fig. 9, being a section on the line A—B of Fig. 5, and Fig. 10 being a section on the line C—D of Fig. 7.

The loom shown in Figs. 1 and 2, which may also be used as a feeler rod for warp stop motions consists essentially of a shaft 1 formed of double steel wire or the like which at both ends is provided with thin

steel plates 2 having lengthened ears 3 for receiving the loom rods, the thread eye 4 being arranged along the shaft 1 between the steel plates. The small steel plates are 5 thinner than a single wire of the double wire shaft and are at one end provided with a slot 5 ending inwardly in a circular broadened portion 6 in which the ends of the wire shaft 1 are arranged with the parts 7 and 10 8 spread out therein (see Figs. 5 to 9). The small plates are connected with the parts 7 and 8 by solder and the heald at the connection between the heald shaft and the small plates is only as thick as the thickness 15 of a single wire or the wire heald.

The loom healds are made as follows: By means of a stamp the slot 5 having an enlarged portion 6 is stamped out of a steel plate 2 or the like (Fig. 3). Then by means 20 of a suitable instrument the wire ends of the heald shaft, the two wires of which are soldered together in known manner, are separated and bent around into annular form. The shaft of the heald is at this place split 25 along its length for a short distance so that springy portions 7 are formed on the two semiannular portions 8 (Fig. 4), which will correspond in shape to the cut-away portion 5, 6 of the small plate 2.

30 The ends 7 and 8 of the wires forming the heald thus shaped are pressed into the slots 5 and 6 of each of the small plates 2 under pressure so that the two springy portions 9 and the two annular halves 7 are pressed 35 one toward the other (5 and 6). The pressing in of the parts is such that the parts 7 and 8, after being pressed in, lie as much on one side of the plate as on the other (see Figs. 6 and 9). As the parts 7 and 8 40 of the shaft tend to spring apart from one another they will hold the small plates sufficiently securely to prevent displacement of the parts during transporting of the shafts with the small plates from one point to another. Consequently it is possible to pass 45 the shafts with the plates to a soldering apparatus by mechanical means where the parts 7 and 8 are soldered to the plates 2. The space inclosed by the semi-annular portions 7 as also the space between these, and the parts 8 and the plates 2 will be filled 50 with solder (Fig. 10) and finally the excess solder will be removed or will be leveled between the parts 7 and 8.

55 By this means the shafts at the place of connection with the plates 2 will at the most be only as thick as a single wire of the double wire heald. It is therefore possible to arrange a greater number of healds than 60 hitherto possible along a shaft, or alternatively to provide a greater free space between the healds and thereby to prevent a mutual friction or interference between the individual healds. The ears 3 of the steel

plates may be formed longer than the corresponding ears in previous constructions of wire healds so that the healds may be given greater motion and consequently an improved guiding of the heald rods may be obtained.

The cut-away portions in the steel plates 2 and the shape of wire ends of the heald pressed into them may take other shapes than those shown particularly by way of example. The small plates 2 at the lower 75 ends of the healds can be extended for a greater length unbroken in order that when the heald is used as a feeler rod this part will have the necessary resistance to bending on the member of the stop motion which 80 comes into contact on the breakage of a thread.

I claim:

1. A loom heald comprising a heald shaft of double steel wires the ends of which are 85 bent away from one another and ears at either end of the heald shaft formed of small steel plates and provided with corresponding slots in which said ends of the wires are arranged and connected to the 90 plates by soldering.

2. A loom heald, comprising a heald shaft of double steel wires the ends of which are bent away from one another and suitably shaped, and ears at either end of the heald 95 shaft formed of small steel plates and provided with slots having a broadened end in which the correspondingly shaped ends of said wires are arranged and connected to the plates by soldering.

3. A loom heald, comprising a heald shaft of double steel wires the ends of which are bent away from one another and having a straight portion and semi-annular bent 105 portions, and ears at either end of the heald shaft formed of small steel plates each provided with a longitudinally running slot the enlarged end of which being circular in which slots the ends of said wires are arranged and connected to the plates by soldering.

4. A loom heald, comprising a heald shaft of double steel wires the ends of which are bent away from one another and having a straight portion and semi-annular bent 115 portion, and ears at either end of the heald shaft formed of small steel plates each provided with a longitudinally running slot, having an enlarged circular end the ends of said wires being arranged in the slots and 120 connected to the plates by soldering, the space between the semi-annular wire parts being filled in level with solder.

5. A process for manufacturing loom healds comprising bending out the ends of the wire shafts by splitting the double wire, stamping a correspondingly formed slot out of steel plates, pressing the bent out ends of

the wire shaft into the slot and subsequently connecting said ends to the plates by soldering.

6. A process for manufacturing loom
5 healds, comprising bending away from one
another the ends of the wire shaft to form
an annulus and spreading apart the two
wire ends for a short distance by splitting

the double wire, stamping a slot with a circular extension out of small steel plates, 10
pressing the springy ends of the wires into
the slots of said plates, and securing the in-
serted ends to the plates by soldering.

In testimony that I claim the foregoing
as my invention, I have signed my name.

ALPHONS ZIPFEL.
